UNITED STATES PATENT OFFICE

PIERRE MAILLEBUAU, OF LA NEUVILLE EN HEZ, FRANCE

PUMP

Application filed July 25, 1930, Serial No. 470,555, and in France September 24, 1929.

The present invention relates to a pump of the suction and discharge type for elevating water and other liquids.

Known pumps have been devised in which the piston operates under hydraulic control, which latter comprise pipes of small diameter by which the body of the pump is supplied with the fluid under pressure. If the water is to be elevated to a great height, thus requiring a great pressure, the packing of the pump is subject to a very rapid wear, and the pipes will often burst.

The pump, the object of the present invention, obviates all such defects, and it is essentially characterized by the fact that it consists of two pipes for the ascent of the liquid, each comprising a main pump body or barrel provided with a piston, the same being connected together at the lower part after the manner of communicating vessels; the hydraulic control of the piston contained in one of the vertical pipes being effected by the column of liquid in the other pipe, and inversely.

The following description, together with the accompanying drawings, will show the manner in which the invention may be carried into effect.

Fig. 1 is a diagrammatic view of the pump. Fig. 2 is a section, on a larger scale, of the controlling piston.

As will be observed in the figures, the pump, the object of the invention comprises two ascending pipes a^1 , a^2 , which are connected together at the lower part. The two pipes are provided with similar parts, which will be enumerated for the pipe a^1 . At the upper part is a controlling piston c^1 , which is actuated in the known manner by a crank-shaft d or by any other means. At the lower part are disposed two pistons e^1 , f^1 , which are mounted on the same rod. The piston e^1 receives the thrust of the piston c^1 . The piston f^1 is the pump piston properly so called. A branch pipe g^1 is mounted on the respective sides of the stroke of the piston e^1 and it is immersed at h^1 in the water of the well; clack-valves i^1 , j^1 are disposed in said branch g^1 . At the upper part of the ascending pipe, and at the upper end of the

stroke of the piston c^1 is branched a pipe k^1 provided with a clack valve l^1 and serving for the evacuation of the pumped water.

The piston c^1 , or the piston c^2 which is identical, is shown on a larger scale in Figure 55 2. This piston is constituted as a delivery valve in such manner as to be traversed by the water during its upward stroke. The rod m carries an axle n on which is slidable the head o of the piston properly so called, it being fitted with a packing member p held by a disk q . During the down stroke, the head o is applied against the circular packing member m^1 of the rod m , and the piston operates normally for the compression of the water situated below it. During the up stroke, the rod m rises, and the head o slides and comes into the shown position of the figure; a spring r aids in this motion, and the water situated below the piston proceeds 60 freely in the direction of the arrows and thus attains the discharge pipe k^1 . A washer s screwed to the rod n and a packing member t limit the sliding of the head o .

The piston c^2 might be designed as an ordinary piston, but in this case, a special clack valve under positive control will be substituted for the ordinary clack valve l^1 of the pipe k^1 which leads to the lower part of the stroke of the piston c^1 .

The lower pistons f^1 , f^2 are connected together by a rocking device by which they will maintain their respective positions in the pipes a^1 , a^2 in spite of the leakage which may result from the wear of said pistons. A 85 link u^1 , u^2 is pivoted to the lower part of the respective pistons f^1 , f^2 , and the lower ends of said links are pivoted to the respective ends of a rocking lever v which is pivotally mounted on a stationary axle. The said lever and links are very light, and are subjected to no strains, as the pressure is imparted by the liquid contained in the connecting pipe b .

The operation of the pump is as follows: 95 The water is supposed to fill the two pipes a^1 , a^2 , and also the pipe b connecting them together, and when the piston c^2 descends, (in the case of the figure) the column a^2 operates as a hydraulic control for the piston 100

*f*¹. The piston *f*², when descending, causes the suction of the water in the pipe *h*² whilst the pressure imparted by *b* to the piston *f*¹ effects, in the direction of the arrow, the discharge of the water situated above the piston *f*¹ and contained in the chamber *h*¹. The water proceeds through the valve *i* into the pipe *a*¹ whence it traverses the piston *c*¹ in order to reach the offtake pipe *k*¹. During the next half revolution of the crank-shaft, the function is inverted, and so on.

It is observed, that in addition to the advantages specified, the arrangement of communicating vessels provides at each instant for the equilibrium of the column of water contained in one of the pipes by the column of water situated in the other pipe.

Obviously, modifications in detail may be employed, without departing from the principle of the present invention.

What I claim is:

1. In a liquid pump of the character described, the combination of two upright pipes connected together at their lower ends, 25 a piston operating in the upper portion of each pipe, means in the construction of each piston to permit liquid to pass through during each descending stroke, means actuating said pistons to alternately displace the 30 column of liquid in said pipes, two pistons disposed in the lower portion of each pipe and operating with the displacement of the column of water in the other pipe, separate pipes in communication with the first pipes 35 and provided with inlet and outlet valves to control liquid pumped by the lower members of the lower pistons.

2. A pump, as claimed in claim 1, including means connecting the lower pistons together to insure alternate movement thereof.

3. In a liquid pump of the character described, the combination of a U-shaped pipe having a T-branch pipe for each upright arm, a pipe continuing from the upper end of 45 the cross piece of each T-branch and in communication with the upright arm at a point spaced above the connection to the T-branch pipe, an inlet and an outlet valve for the lower and upper ends respectively of the 50 cross piece of each T-branch pipe, two pistons in each upright arm operating respectively above and below the connection with the T-branch, means connecting the two pistons in one arm with the two pistons of the other 55 arm to cause opposite reciprocating movement in one set of pistons with respect to the movement in the other set, and a reciprocating valve piston in the upper portion of each upright arm and operating above the pipe 60 connection between the T-branch and arm, whereby the column of liquid in each arm between the upper piston and the upper member of the lower pistons imparts the downward movement of the upper piston to 65 the lower pistons, while the lower member of

the latter in its downward movement draws liquid in its wake past the inlet valve into the T-branch.

In testimony whereof I affix my signature.

PIERRE MAILLEBUAU.
